ATTORNEY

UNITED STATES PATENT OFFICE.

CHARLES F. ROBINSON, OF SAN FRANCISCO, CALIFORNIA.

MOTOR-CAR AXLE.

1,107,448.

Specification of Letters Patent. Patented Aug. 18, 1914.

Application filed April 17, 1912. Serial No. 691,537.

To all whom it may concern:

Be it known that I, CHARLES F. ROBINSON, a citizen of the United States, residing in the city and county of San Francisco and State of California, have invented a certain new and useful Improvement in Motor-Car Axles, of which the following is a specification.

My invention relates to an improvement 10 on those car wheel axles on which the liner of the motor casing of a motor propelled car bears, and it is applied after the journal parts of the axle on which the liner bears, have worn out or have become too 15 small.

The object of my improvement is to prolong indefinitely the life of the axles, thereby saving much labor and material. I attain this object by metal plates inlaid, welded or brazed in, and made solid with, the 20 axle where it has been worn by the liner of the casing of the motor, thus restoring the axle throughout its entire length to its original form and efficiency. In such metal 25 plates consists, essentially, my improvement.

It is illustrated in the accompanying drawings, embodying my improvement, in which—

Figure I is a side view of the axle of 30 a motor car on which the liner of the casing bears, broken into two parts, the wheels and the casing of the motor being omitted, one of said two parts showing one of said worn journal parts without the said metal plates, 35 and the other of said two parts, the other of said worn journal parts with the metal plates inlaid therein, partly broken away and sectioned transversely through the center. Fig. II is a transverse section through

the center of a metal plate composed of a 40 number of pieces. Fig. III is a side view of a metal plate as it appears separate from the axle.

"A" represents the axle of a motor car wheel; "B," the worn journal parts of the 45 axle; "C," the metal plate, (Figs. II and III) before, and (Fig. I) after inlaid in the worn journal parts. The metal plate "C" is metal formed to fit the worn journal parts of the axle and is of such size and 50 shape as to restore the axle to its original form and efficiency. It may consist of one piece or of two or more pieces (preferably four, as shown in the drawing) for its convenient insertion. The pieces forming the 55 plate may be secured to each other and to the worn journal parts of the axle in any one of the well known ways of securing metal to metal.

I claim:

The herein described method of repairing worn axles which consists in cutting down an intermediate worn portion of the axle to form a reduced portion of a definite length, fitting about the cut down portion of the 65 axle one or more filling segments, each of a length equal to the length of the reduced portion, the segments when fitted about the reduced portion completely ensheathing the same, permanently uniting the said segments to the surface of the reduced portion and to each other, and finally truing down the segments flush with the unworn surface of the axle.

CHAS. F. ROBINSON.
